UNITED STATES PATENT OFFICE.

WILLIAM T. SHERER, OF CHICAGO, ILLINOIS.

DISPLAY CASE.

Application filed June 20, 1925. Serial No. 38,480.

My invention relates to an improvement in display cases and particularly to a case of the type wherein a plurality of separate slide gates are positioned to the rear of the case. One object of my invention is to provide a case into which access may be had into a plurality of compartments at the same time. Other objects will appear from time to time in the course of the specification and 10 claims.

I illustrate my invention more or less diagrammatically in the accompanying drawings wherein—

Figure 1 is an elevation;

Figure 2 is a horizontal section; and

Figure 3 is a partial plan view of the bottom member of the case.

Like parts are illustrated by like symbols throughout the specification and drawings.

Referring to the drawings, A A¹ are any suitable end panels or members, which may be provided, if desired, with glass or other translucent material.

B B¹ and B² are the transparent front 25 panels of the case.

C is any suitable base, and C¹ any suitable top member.

The case may be divided into a plurality of separate compartments, herein shown as 30 three, for example by the partitions D and D¹. Since it is preferred, in the use of my cases, for example, for bakery purposes, to prevent the passage of air from one compartment to another, I may provide any suitable felting or packing D² D³ at the inner ends of 35 such compartments in order to make a tight connection with the doors below described. Any suitable material may be used, but I find a relatively thin layer or cushion of felt 40 to provide a sufficiently tight connection.

It will be noted that the end panels A A¹ are of the same length, and that the partitions D D¹ are somewhat shorter than the end panels.

E is a single track extending from end to end of the case and provided with a plurality of sliding doors E¹ and E² having any suitable felting or packing E³, E⁴ on the ends, the former abutting against the end panel A and the latter against the end panel A¹ when in closing position.

G is an outer track extending from end to end of the case and having on it two sliding door sections G¹ and G². These two sec-

tions together form a single door about the 55 same length as the doors E¹ E². They may be provided with an overlapping fit as by the flanges G³ G⁴ and any suitable felting or packing G⁵ may be used. G⁶ is any suitable felting or packing on the ends of the 60 doors E¹ E² or of the sections G¹ G² the purpose of which is to provide a relatively air tight closure, when the doors are all in closing position.

When it is desired to have access to but 65 one compartment at a time the appropriate door or door section is laterally moved along the track E or the track G as the case may be. When it is desired to have simultaneous access to the end compartments the door E¹ 70 is moved to the right and the door E² to the left, as shown in Figure 2 until their ends meet in the middle of the case. When it is desired to have access simultaneously to the central compartment and to one of the end compartments the door to the end compartment is moved until its center is opposite the compartment D or D¹, as the case may be, and the section G or G¹ which does not overlap with the door is moved along the 75 track G.

It will be realized that whereas I have illustrated a practical and operative device that nevertheless many changes may be made in the size, shape, number and disposition of parts without departing from the spirit of my invention. I wish my description and drawings to be taken as in a broad sense diagrammatic or illustrative, rather than as limiting me to the specific showing herein 80 made. In particular it will be realized that whereas I have illustrated a display case which is separated into a plurality of air tight compartments, I do not limit myself to such structure. Obviously my arrangement 85 of gates may be employed with a counter which is only partially so divided, or which has no partitions at all.

I claim:—

1. In a display case having a plurality of 100 separate compartments, end panels and intermediate partitions, a plurality of tracks extending from end to end of the case, a plurality of doors adapted to slide along one of said tracks, each door being of substantially the same length as the width of one compartment, a pair of doors sliding along another of said tracks, the effective length 105

of said pair of doors being substantially equal to the width of one compartment.

2. In a display case, end panels and front and top members, a plurality of tracks extending from end to end of the case, a plurality of doors adapted to slide along one of said tracks, a pair of doors adapted to slide

along another of said tracks, the effective length of said last mentioned pair of doors being equal to the length of one of the doors ¹⁰ sliding on said first mentioned track.

Signed at Chicago, county of Cook and State of Illinois, this 16th day of June 1925.

WILLIAM T. SHERER.
